UNITED STATES PATENT OFFICE.

GEORGE W. TURNER, OF BOSTON, MASSACHUSETTS.

DESIGN FOR A MUSICAL-INSTRUMENT CASE.

SPECIFICATION forming part of Design No. 13,603, dated February 6, 1883.

Application filed December 4, 1882. Term of patent 3½ years.

To all whom it may concern:

Be it known that I, GEORGE W. TURNER, a citizen of the United States, residing at Boston, Massachusetts, have invented and produced a certain new and useful Design for Cases for Mechanical Musical Instruments, of which the following is a specification.

This invention relates to the case or cabinet of a mechanical musical instrument, such as 10 the "harmonette," "organina," and others of like nature; and it consists of such a case or cabinet composed of parallel end uprights and side pieces, all inclosing the working parts of the instrument, and having each of said end 15 uprights made with a rounding top edge and the side and bottom edges formed with escallops, in combination with the side pieces, arranged at a vertical angle of inclination, running in directions to intersect each other, if extended downward, and being connected to the 20 top or upper part by other horizontally-inclined pieces, substantially as hereinafter described, and shown in the accompanying plates of drawings, in which—

25 Figure 1 is an end elevation. Fig. 2 is a vertical cross-section. Fig. 3 is a plan view, and Fig. 4 is a side elevation.

In the drawings, A A and B B represent respectively the parallel end uprights and the 30 side pieces of a case or cabinet inclosing and carrying the working parts of a mechanical musical instrument, such as a "harmonette" or "organina," so called. Each end upright A is rounding at its top edge, a, and along

such edge, and also the side or vertical edges, 35 b, and the bottom edge, c, of each upright A, there are a series of escallops, d, all so as to give a graceful and pleasing appearance thereto. The side uprights, B, are at a vertical angle of inclination, so that if they be extended downward they will intersect each other, and above these sides of the uprights are horizontally-inclined pieces C, connecting the side uprights with the upper or top parts, D, of the instrument. 40

Having thus described my new and original 45 design, what I claim, and desire to secure by Letters Patent, is—

1. A new design for a cabinet or case for 50 mechanical musical instruments, consisting of end pieces, A A, having escalloped edges a, b, and c, and side pieces, B B, arranged at an angle of vertical inclination, substantially as described.

2. A new design for a cabinet or case for 55 mechanical musical instruments, consisting of end pieces, A A, having escalloped edges a, b, and c, side pieces, B B, arranged at an angle of inclination, and inclined pieces C, all substantially as described. 60

In testimony whereof I have hereunto set my hand in the presence of two subscribing witnesses.

GEORGE WALTER TURNER.
